CRYSTAL DIODE

Paul E. Gates, Danvers, Mass., assignor to Sylvania Electric Products Inc., a corporation of Massachusetts

Application April 5, 1949, Serial No. 1,810

Term of patent 14 years

(Cl. D26—8)

To all whom it may concern:

Be it known that I, Paul E. Gates, a citizen of the United States of America, residing at Danvers, in the county of Essex in the State of Massachusetts, have invented a new, original, and ornamental Design for a Crystal Diode, of which the following is a specification, reference being had to the accompanying drawing, forming a part thereof, in which:

Fig. 1 is a lateral elevation of a crystal diode embodying my new design, the enclosed elements being visible through a transparent wall portion of the diode; and

Fig. 2 is a perspective view of the diode in Fig. 1, the enclosed parts not being visible from the angle shown.

The characteristic features of my design are shown in solid lines in my drawing.

What I claim is:

The ornamental design for a crystal diode, substantially as shown and described.

PAUL E. GATES.
